DESIGN FOR AN OUTBOARD MOTOR HAVING A POWER HEAD

Elmer C. Kiekhaefer, Cedarburg, Wis.

Application September 5, 1947, Serial No. 141,231

Term of patent 14 years

(Cl. D71—1)

To all whom it may concern:

Be it known that I, Elmer C. Kiekhaefer, a citizen of the United States, residing at Cedarburg, in the county of Ozaukee and State of Wisconsin, have invented a new, original, and ornamental Design for an Outboard Motor Having a Power Head, of which the following is a specification, reference being had to the accompanying drawing, forming part thereof.

In the drawing:

Fig. 1 is a side elevation of an outboard motor having a power head embodying my new design; Fig. 2 is a front elevational view thereof; Fig. 3 is a top plan thereof; and Fig. 4 is a fragmentary rear elevation thereof. The characteristic features of my design reside

in the portions shown by means of full lines in the drawings.

I claim:

The ornamental design for an outboard motor having a power head, as shown and described.

ELMER C. KIEKHAEFER.
